(57) **CLAIM**

The ornamental design for a toy aircraft, as shown and described.

DESCRIPTION

FIG. 1 is a perspective view of a toy aircraft showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is bottom view thereof.

The part of the photograph shown in a coarser dot pattern within the broken-line perimeter, as well as the broken-line perimeter itself, illustrates a portion of the tractor that forms no part of the claimed design.
